UNITED STATES PATENT OFFICE.

AUGUSTUS H. WOODRUFF, OF IRVINGTON, NEW JERSEY, ASSIGNOR OF
ONE-HALF TO FRANK F. SMITH, OF NEWARK, NEW JERSEY.

GRAVITY-BOLT AND FUSIBLE CONNECTION FOR METALLIC FRAMES AND WINDOWS THEREFOR.

No. 815,774.

Specification of Letters Patent.

Patented March 20, 1906.

Application filed May 12, 1905. Serial No. 260,149.

To all whom it may concern:

Be it known that I, AUGUSTUS H. WOODRUFF, a citizen of the United States, residing at Irvington, in the county of Essex and State 5 of New Jersey, have invented certain new and useful Improvements in Gravity-Bolts and Fusible Connections for Metallic Frames and Windows Therefor; and I do hereby declare the following to be a full, clear, and exact description of the invention, such as will enable others skilled in the art to which it 10 pertains to make and use the same, reference being had to the accompanying drawings, and to numerals of reference marked thereon, 15 which form a part of this specification.

This invention has reference generally to improvements in windows, skylights, and the like, such as doors and shutters.

The invention relates more particularly to 20 a novel means in the form of a fusible connection which is used with the devices for retaining the window, skylight, door, and the like in an open relation, but which is melted in case of excessive heat due to fire and causes 25 the automatic closing of the window, skylight, door, shutter, and the like.

My present invention has for its principal object to provide in connection with a window, skylight, door, shutter, and the like a 30 simple and cheaply-constructed lock and bolt which works by gravity to retain the window or the like in its closed position, but can be readily manipulated to open the window or the like, all with a view of dispensing with 35 the use of springs, which are apt to become weak and useless due to corrosion or when exposed to fire, to be used in conjunction with a fusible connection which is severed in case of fire to automatically close the window or the 40 like.

A further object of this invention is to provide in connection with a pivoted or other suitably-operated window, skylight, door, shutter, or the like a novel and simply-arranged fusible connection or means which is effected from the heat produced upon either side of the fixture, as a window, skylight, door, and the like, and melts away, whereby such fixture is automatically closed.

Other objects of this invention are simplicity in construction, a reduction of parts to a minimum, and the ease and readiness with which any one of the fusible connections can

be replaced when destroyed by the heat from a fire.

With the various objects of my invention in view the same consists in the novel arrangement and construction of fusible devices in combination with the fixture for automatically closing the same in case of fire or excessive heat.

The invention consists, furthermore, in the novel arrangements and combinations of the various devices and parts, as well as in the details of the construction of the same, all of 65 which will be hereinafter more fully described and then finally embodied in the clauses of the claim, which are appended to and which form an essential part of this specification.

The invention is clearly illustrated in the 70 accompanying drawings, in which—

Figure 1 is a face view of a metallic window-frame and a pair of metallic sashes and their windows pivotally arranged, so as to swing in said window-frame, said windows being shown in their opened relation, by means of a flexible connection connected with the lock mechanism and the fusible separating device. Fig. 2 is a similar view of the same parts, showing the windows closed 8c when the flexible connection has been detached by the melting or fusing of the said fusible connections. Fig. 3 is a transverse vertical section of the upper part of the window-frame and window, said section being 75 taken on line 3 3 in Fig. 1 and showing the window held open; and Fig. 4 is a similar sectional representation of the same parts, but showing the window held in its locked or closed position by the gravity-bolt in the upper part of the window-frame. Fig. 5 is a vertical section, on an enlarged scale, of the upper portion of the window-frame and window-sash, showing the gravity-bolt in its locked engagement with the parts in the lock-casing, the said bolt and certain parts within the lock-casing being shown in elevation, while other parts in said lock-casing are represented in section. Fig. 6 is a top view of the gravity-bolt and the guide-plate in which it is movably arranged. Fig. 7 is a detail vertical section of the lock-casing and part of the metallic window-frame, said section being taken on line 7 7 in Fig. 5 looking in the direction of the arrow X, the latch of the locking mechanism, however, being shown in its 90 95 100 105

raised position. Fig. 8 is a side view of the screw-threaded end portion of a rod used with the device and a fusible nut arranged upon said screw-threaded end portion, and 5 Fig. 9 is a similar view of said rod with the fusible nut shown detached. Fig. 10 is a sectional representation of a lock-casing provided with a lock mechanism of a slightly-modified form of construction, but still embodying the principles of the present invention.

Similar characters of reference are employed in all of the said above-described views to indicate corresponding parts.

15 Referring now to the several figures of the drawings, the reference character 1 indicates a metallic window-frame of any usual construction, which is provided with a suitably-formed hollow portion 2, forming a chamber, 20 substantially as shown in Figs. 2, 3, and 4 of the drawings. In the lower wall or base 3 of this portion 2 is a suitable hole or opening 4 for the purposes to be presently set forth. The sheet metal from which the frame 1 is 25 made is also provided at the back, at a point below said portion 2, with a suitably-formed and laterally-extending angular shield or rain-drip 5.

One or more window-sashes 6, made of 30 sheet metal, are pivotally suspended or swung in the opening of the window-frame, each sash having an upper hollow portion 7 and a lower hollow portion 8, respectively provided with the channel-shaped receiving 35 edges 9 for securing the usual window-glass 10 between said upper portion 8 and lower portion 9. Suitable stops 11 may also be provided at the back on opposite sides of the opening in the window-frame 1, against 40 which the window-sash is swung, when opened, to limit the pivotal movement of the window, as clearly shown in Fig. 3 of the drawings.

Suitably secured in the upper hollow portion 7 of the window-sash during the process of bending the sheet metal into shape is 45 a lock-casing and its mechanism contained therein, as clearly indicated in the several figures of the drawings. This casing usually 50 consists of two sections 12 and 13, as indicated in Fig. 7 of the drawings, each section being provided with a perforated flange 14, screw-bolts 15 and nuts 16 being employed for securing the sections of the lock-casing 55 against the inner face of one of the sides of the portion 7, substantially as shown in Figs. 3, 4, 5, and 7 of the drawings. One of said sections, as 12, is provided with screw-receiving holes 17, while the other section 13 60 is formed with interior posts 18, provided with screw-threaded sockets 19, placed directly opposite the screw-holes 17 for the reception of screws 20, by means of which the two sections 12 and 13 are secured together, as 65 shown. A cover or plate 21, provided with a

holding-flange or lugs 22, is arranged over the upper open portion of the two connected sections 12 and 13, the said cover or plate 21 being held in place by said flange or lugs 22, and by the inner face of the upper wall of 70 said portion 7. The said cover or plate 21 is provided with an opening 23, and in said upper wall of the portion 7 is a correspondingly-formed opening 24, which registers with the said opening 23, and thereby forms one 75 continuous opening through said upper wall of the portion 7 and said cover or plate 21. Pivotedly arranged upon the upper post 10 of the said section 13 is a latch 25, having a recess 26 in its pivoted portion and provided with 80 a lifting end or portion 27. Normally the said latch 25 is in the position indicated in Figs. 4 and 5 of the drawings; but when the window is opened said latch is actuated in the manner to be hereinafter more fully described, whereby its lifting end or portion 27 is moved into the opening formed by the openings 23 and 24, previously mentioned, as clearly indicated in dotted outline in said Fig. 5 and in section in Fig. 7. 90

Suitably secured upon the inner face of the base of the hollow portion 2 of the frame 1 is a plate 28, provided with an upwardly-extending guiding-socket 29. This socket is preferably of an angular configuration in 95 cross-section, as indicated in the dotted outline in said Fig. 6, which is preferably wider at the top than at the bottom and has a pin 30 extending across its guiding-opening. Movably arranged within the said guiding-socket 29 is a bolt 31, having an elongated opening 32, through which the said pin 30 extends and upon which the said bolt is movably arranged. The lower holding portion of said bolt has a rounded edge 33, and upon its upper end it may be provided with a head or enlargement 34, which normally rests upon the upper marginal edge of the said guiding-socket 29 and by gravity forces the lower holding portion of the bolt 31 into and 100 through the previously-mentioned openings 23 and 24 to retain the window-sash in its closed relation in the window-frame in the manner clearly indicated in Figs. 4 and 5 of the drawings. 110

115 Referring now more particularly to Fig. 5 of the drawings, it will be seen that in the front and rear walls of the said upper hollow portion 7 of the window-sash I have placed suitably-disposed and upwardly-inclining 120 openings 35 and 36, respectively, the two sections 12 and 13 being, respectively, provided with semicircular or other suitably-shaped guide portions 37 and 38, in which is movably arranged an upwardly-extending and 125 angularly-inclining tube 39, provided with a teat or projection 40, which extends in operative engagement into the recess 26 of the latch 25. Within the said tube 39 is a rod 41, having an upper shouldered portion 42, 130

which has a screw-threaded part 43 for the screwing thereon of a nut 44. The lower end portion of the said rod 41 extends from the opening 35 in the front piece of the portion

- 5 7 of the window-sash and is provided with a receiving eye or loop 45. From an inspection of the drawings it will be seen that the said nut 44 under normal conditions rests upon the upper edge of the tube 39 to prevent the displacement of the said rod 41 from said tube 39. It will also be noticed that the weight of the pivoted latch 25 under normal conditions, indicated in Fig. 5 of the drawings, retains the tube 39 and parts connected therewith in the raised position shown in said figure. The said nut 44 may be a fusible nut, any form of nut which will fuse readily being used. The form of fusible nut 44 which I prefer to use, however, is shown in Figs. 8 and 9, in which the said nut

20 consists of an inner screw-threaded ring 46 and a nut-shaped member 47, provided with an opening 48, so as to be slipped over the said ring 46 and united thereto by means of a layer 49 of easily-fusible metal, as clearly represented in said Fig. 8; but of course it will be understood that any other suitable construction of fusible nut may be employed, if desired.

- 25 30 To actuate the lock mechanism and cause the latch 25 to lift the bolt 31 from its locked or holding engagement with the upper portion 7 of the window-sash when it is desired to open the window, a suitable flexible connection 50, having at its lower end a ring 51 or other means adapted to be brought in holding engagement with a hook, pin, or other projection, as 52, upon the window-frame is employed. If desired, a fusible plate or link

- 40 45 50 55 53 may also be arranged between the links or other portion of the said flexible connection, as shown in Figs. 1, 3, and 4 of the drawings.

The operation of the device will be clearly understood from an inspection of Figs. 3, 4, 45 and 5 and need not be more particularly described, and when either or both of the fusible devices, as the nut 44 and the plate or link 53, are used it will be seen that excessive heat or a fire on either side of the wall in

- 50 55 60 65 70 which the window is placed will immediately melt the said fusible nut 44 or the plate or link 53, whereby in either case the holding connection is destroyed and the sash and its window at once returns to the closed position in the frame 1, as clearly indicated in said Fig. 4, the gravity-bolt 31 being first raised by contact with the upper portion of the sash

6. The bolt immediately drops back into the holes or openings 24 and 23, and there- 60 by thoroughly secures the closed window in its securely-locked relation in the frame 1. When the fusible nut 44 only is destroyed, then the said rod 41 is withdrawn entirely out of the tube 39, and the window in like manner automatically returns to its closed

position in the frame 1. The fire will thus be held upon the one side of the wall and may be readily checked from spreading to the other side of the window. The fusible nut or the plate or link 53 when once destroyed can be 70 readily replaced at slight cost and the mechanism again restored for further usefulness. It will also be seen that the said shield or rain-drip 5 protects the fusible nut 44 against corrosion by preventing the rain and the like 75 from beating upon the nut.

In Fig. 10 I have illustrated a slightly-modified arrangement and construction of the locking mechanism. In this construction, in which the general construction of the 80 parts is practically the same as the hereinabove described, the tube 39 is movably arranged upon a long support 54, extending from the opening 35 to the opening 36 in the opposite sides of the casing. The latch 25 in 85 this construction is also of a slightly different configuration, being provided with a long curved edge 55, on which the holding end of the bolt 31 rides, as indicated in the dotted outline in said Fig. 10, and is raised and lowered in a similar manner to that previously described.

Having thus described my invention, what I claim is—

1. The combination, with a metallic frame 95 and a fixture, as a window, door, or the like, adapted to oscillate in said frame, said fixture being provided with an upper hollow portion, of a locking mechanism in said hollow portion, a slidably-arranged rod extending across said 100 hollow portion, said rod having its respective ends projecting from the opposite sides of said fixture, a fusible nut on one of said projecting ends of the rod, and a flexible connection upon the other projecting end of said 105 rod for actuating said locking means, substantially as and for the purposes set forth.

2. The combination, with a metallic frame and a fixture, as a window, door, or the like, adapted to oscillate in said frame, said fixture 110 being provided with an upper hollow portion, of a locking mechanism in said hollow portion, a slidably-arranged rod extending across said hollow portion, said rod having its respective 115 ends projecting from the opposite sides of said fixture, a fusible nut on one of said projecting ends of the rod, a flexible connection upon the other projecting end of said rod for actuating said locking means, and a second 120 fusible device in said flexible connection, substantially as and for the purposes set forth.

3. The combination, with a metallic frame and a fixture, as a window, door, or the like, pivotally connected with said frame, of means for holding said fixture in an open position 125 in said frame, comprising a rod extending through said frame, said rod having a screw portion, a screw-threaded ring thereon, a nut-shaped member slipped over said screw-threaded ring, and a layer of fusible metal 130

between said screw-threaded ring and said nut-shaped member, substantially as and for the purposes set forth.

4. The combination, with a metallic frame and a fixture, as a window, door, or the like, pivotally connected with said frame, of a flexible connection upon the one side of said frame and fixture for holding said fixture in an open position in said frame, a fusible device in said flexible connection, and a second fusible device arranged against the opposite and outer side of said fixture for automatically closing said fixture when either of said fusible devices is melted, substantially as and for the purposes set forth.

15 5. The combination, with a metallic frame and a fixture, as a window, door, or the like, pivotally connected with said frame, of a flexible connection upon the one side of said frame and fixture for holding said fixture in an open position in said frame, a fusible device in said flexible connection, and a second fusible device comprising a rod extending laterally through said fixture from the front to the rear or outer side of the same, and a fusible nut upon the free end of said rod which extends from said rear or outer side of the fixture, all arranged substantially as and for the purposes set forth.

30 6. The combination, with a metallic frame and a fixture, as a window, door, or the like, pivotally connected with said frame, of a flexible connection upon the one side of said frame and fixture for holding said fixture in an open position in said frame, a fusible device in said flexible connection, and a second fusible device comprising a rod extending laterally through said fixture, from the front to the rear or outer side of the same, said rod having a screw portion which extends from said rear or outer side of the fixture, a screw-threaded ring thereon, a nut-shaped member slipped over said screw-threaded ring, and a layer of fusible metal between said screw-threaded ring and said nut-shaped member, substantially as and for the purposes set forth.

45 7. The combination, with a hollow metallic frame and a fixture, as a window, door, or the like, pivotally connected with said frame, said fixture having a hollow part, provided with guiding portions, of a tube movably arranged in said guiding portions, a latch in said hollow part, means connected with said tube for actuating said latch, a gravity-bolt in said hollow frame, and means connected with said tube for actuating said latch and raising the said bolt from holding engagement with the pivoted fixture and holding said fixture in an open position in said frame, and a fusible device for automatically closing said fixture when said fusible device is melted, substantially as and for the purposes set forth.

55 8. The combination, with a hollow metallic frame and a fixture, as a window, door, or the

like, pivotally connected with said frame, said fixture having a hollow part, provided with guiding portions, of a tube movably arranged in said guiding portions, a latch in said hollow part, means connected with said tube for actuating said latch, a gravity-bolt in said hollow frame, and means connected with said tube for actuating said latch and raising the said bolt from holding engagement with the pivoted fixture and holding said fixture in an open position in said frame, comprising a rod extending through said tube, and a fusible nut upon the free end of said rod for automatically closing said fixture when said fusible nut is displaced, substantially as and for the purposes set forth.

90 9. The combination, with a hollow metallic frame and a fixture, as a window, door, or the like, pivotally connected with said frame, said fixture having a hollow part, provided with guiding portions, of a tube movably arranged in said guiding portions, a latch in said hollow part, means connected with said tube for actuating said latch, a gravity-bolt in said hollow frame, and means connected with said tube for actuating said latch and raising the said bolt from holding engagement with the pivoted fixture and holding said fixture in an open position in said frame, comprising a rod extending through said tube, said rod having a screw portion, a screw-threaded ring thereon, a nut-shaped member slipped over said screw-threaded layer, and a ring of fusible metal between said screw-threaded ring and said nut-shaped member, substantially as and for the purposes set forth.

95 10. The combination, with a hollow frame and a fixture, as a window, door, or the like, pivotally connected with said frame, said fixture having a hollow part provided with guiding portions, of a tube movably arranged in said guiding portions, a latch in said hollow part, means connected with said tube for actuating said latch, a gravity-bolt in said hollow frame, and means connected with said tube for actuating said latch and raising the said bolt from holding engagement with the pivoted fixture and holding said fixture in an open position in said frame, comprising a rod extending through said tube, a holding-nut upon the upper end of said rod, and a fusible nut upon the upper end of said rod, and a flexible connection secured to the lower end of said rod, substantially as and for the purposes set forth.

110 11. The combinations, with a hollow frame and a fixture, as a window, door, or the like, pivotally connected with said frame, said fixture having a hollow part provided with guiding portions, of a tube movably arranged in said guiding portions, a latch in said hollow part, means connected with said tube for actuating said latch, a gravity-bolt in said hollow frame, and means connected with said tube for actuating said latch and raising the

said bolt from holding engagement with the pivoted fixture and holding said fixture in an open position in said frame, comprising a rod extending through said tube, a holding-nut 5 upon the upper end of said rod, and a flexible connection secured to the lower end of said rod, and a fusible device in said flexible connection, substantially as and for the purposes set forth.

10 12. The combination, with a hollow frame and a fixture, as a window, door, or the like, pivotally connected with said frame, said fixture having a hollow part provided with guiding portions, of a tube movably arranged in said guiding portions, a latch in said hollow part, means connected with said tube for actuating said latch, a gravity-bolt in said hollow frame, and means connected with said tube for actuating said latch and raising the 20 said bolt from holding engagement with the pivoted fixture and holding said fixture in an open position in said frame, comprising a rod extending through said tube, a flexible connection secured to the lower end of said rod, a 25 fusible device in said flexible connection, a screw portion upon the upper end of said rod, and a fusible nut on said screw portion for automatically closing said fixture when said nut is displaced, substantially as and for the purposes set forth.

30 13. The combination, with a hollow frame and a fixture, as a window, door, or the like, pivotally connected with said frame, said fixture having a hollow part provided with guiding portions, of a tube movably arranged in said guiding portions, a latch in said hollow part, means connected with said tube for actuating said latch, a gravity-bolt in said hollow frame, and means connected with said 35 tube for actuating said latch and raising the said bolt from holding engagement with the pivoted fixture and holding said fixture in an open position in said frame, comprising a rod extending through said tube, a flexible connection secured to the lower end of said rod, a 40 fusible device in said flexible connection, a screw portion upon the upper end of said rod,

and a fusible nut on said screw portion for automatically closing said fixture when said nut is displaced, said nut comprising a screw-threaded layer, a nut-shaped member, and a ring of fusible metal between said screw-threaded ring and said nut-shaped member, substantially as and for the purposes set forth.

14. The combination, with a metallic frame and a fixture, as a window, door, or the like, pivotally connected with said frame, of means for holding said fixture in an open position, comprising a rod extending laterally through the said fixture and having its end portions projecting from the opposite sides of the fixture, a flexible fastening connection attached to one of the said projecting ends of the rod, a fusible nut upon the opposite projecting end of said rod, and a rain-shield upon the said frame, beneath which the said nut is located when the fixture is closed, substantially as and for the purposes set forth.

15. The combination, with a metallic frame and a fixture, as a window, door, or the like, adapted to oscillate in said frame, said fixture being provided with an upper hollow portion and having guiding members in its opposite sides, one of said guiding members being located higher than the other member, a rod slidably and removably arranged in said guiding members, said rod extending angularly across said hollow portion of the fixture and having its opposite ends extending from the opposite sides of said fixture, a retaining means of a fusible metal upon the upper projecting end of said rod, and a fixture-actuating means attached to the lower projecting end of said rod, substantially as and for the purposes set forth.

In testimony that I claim the invention set forth above I have hereunto set my hand this 9th day of May, 1905.

AUGUSTUS H. WOODRUFF.
